NELS OLSON, OF MINDEN, NEBRASKA.

COMBINATION FRAMING-TOOL.

1,142,527.

Specification of Letters Patent. Patented June 8, 1915.

Application filed June 3, 1914. Serial No. 342,732.

To all whom it may concern:

Be it known that I, NELS OLSON, a citizen of the United States of America, residing at Minden, in the county of Kearney and State 5 of Nebraska, have invented certain new and useful Improvements in Combination Framing-Tools, of which the following is a specification, reference being had therein to the accompanying drawing.

10 This invention relates to a combination framing tool and has for its principal object the production of a device which is adapted to be used more especially by carpenters to enable them to readily and accurately obtain 15 the length and bevels of rafters, thus enabling a carpenter to frame the roof of a building with ease and despatch without the use of a square or bevel and without requiring mental calculations.

20 Another object of this invention is the production of a framing tool having a plurality of sliding members which are adapted to be employed so as to grip and hold a rule in a desired position for facilitating the 25 determining of a certain bevel of a rafter, these sliding members being adapted to slide so as to be easily adjusted when desired.

With these and other objects in view this 30 invention consists of certain novel combinations, constructions and arrangements of parts as will be hereinafter fully described and claimed.

In the accompanying drawings:—Figure 1 is a top plan view of the improved framing tool. Fig. 2 is an elevation of the face portion of the tool. Fig. 3 is a detail perspective view of the rear portion of the tool illustrating the manner in which the same is used for finding the bevels of rafters. 40 Fig. 4 is a section taken on the line 4—4 of Fig. 1. Fig. 5 is a vertical section taken through the upper portion of the tool. Fig. 6 is a detail perspective view of the primary indicating slide. Fig. 7 is a detailed perspective view of the auxiliary clamping slide.

45 Referring to the accompanying drawing by numerals it will be seen that the tool comprises a substantially triangular frame having a base 1 and converging sides 2. The base 1 and sides 2 are formed integral so as to allow the sides 2 to be carried by the base 1 and to be integrally connected at their ends to each other. This base 1 is provided on its forward portions with an upstanding 50 longitudinal rib 3 upon which the shoulder 4 is integrally formed. This rib 3 and

shoulder 4 are of the same thickness and are considerably thinner than the breadth of the base 1 for accommodating the spirit-level 5. This spirit-level 5 has slots 6 formed in the feet 7 wherethrough passes 60 the adjusting means 8 for supporting the spirit-level 5 upon the rear portion of the rib 3. Since the rib 3 is considerably thinner than the base part, the level 5 will be 65 carried so as to be positioned out of the way and to allow the frame to be positioned upon a support and rest evenly without interference from the level. By having the level adjustably supported upon the rib 3 70 the same may be easily adjusted so as to always remain in its correct position and thus provide a means for determining plumb of a rafter or other timber.

75 For the purpose of facilitating the finding of correct angles and bevels by means of this tool, there is provided an indicating slide 9 and a clamping slide 10. This indicating slide 9 has a longitudinally extending slot 11 formed in its body through which a set screw 12 may be passed for adjustably supporting the slide 9 upon the forward face 80 of the base 1. The forward end of the slide 9 is provided with an integrally tapering finger 13 and with a reduced angularly extending ear 14, this ear 14 being formed at a spaced distance from the side edge of the finger 13. When this slide is positioned upon the base 1 the finger 13 will be positioned so as to rest upon the portion of the 85 base 1 upon which the graduations 15 and 16 are formed. The graduations 15 are adapted to facilitate the finding of a correct length for a common rafter while the graduations 16 will facilitate the finding of a correct length for a hip rafter. The rear end of the slide 9 terminates in an upwardly curved lip 17 which is adapted to be grasped for facilitating the sliding or moving of 90 the slide 9 after the set screw 12 has been 100 slidably turned for allowing the movement of the slide. There is also provided an integral tongue 18 formed adjacent the lip 17 which is bent slightly and terminates in a depending spur 19. When the slide is positioned upon the base 1, the spur will be held so as to be positioned upon the surface of the base as clearly disclosed in Fig. 2, owing 105 to the construction of the tongue 18.

110 A lug 20 is fixedly carried upon the base 1 and this lug is provided with a notched portion 21 for the reception of the ear 14

formed upon the slide 9. This lug may be also provided with an under pocket 22 for allowing the finger 13 to pass therethrough when the slide is resting evenly upon the 5 base 1 as disclosed in Fig. 1. The auxiliary or clamping slide 10 is provided with a longitudinal slot 23 through which the set screw 24 may pass for adjustably securing the slide 10 upon the shoulder 4. This slide 10 is also provided at its forward end with an overhanging portion 25 and at its rear end with a handle 26. It will be seen that by the use of the screw 24 this slide may be easily moved and held in a set position for 10 clamping the article which is engaged by the overhanging portion 25. At the connecting portions of the arms 2 is formed a projection 27 while a lug 28 is also fixedly carried by one of the arms 2 as clearly disclosed in Fig. 1. The base 1 may also be provided with graduations as shown at 29 for indicating lengths which may be obtained for ordinary jack-rafters. When it is desired to use this device for obtaining a 15 correct bevel of a common rafter, the indicating slide 9 may be moved so as to indicate the desired height by the graduations on slide 9. A folding rule 30 may then be positioned upon the outer surface of the 20 slide and also allowed to extend across the slide 27. The clamping slide 10 may then be moved into engagement with the rule. The overhanging portion 25 will engage the rule while the rule will bear against a portion of the slide 9 and against the lug 28 carried by one of the arms 2. The slide will 25 then extend at a desired angle so that the tool may be placed upon a rafter as disclosed at 31 in Fig. 3 while the rule may extend across the side edge of the rafter thereby setting forth the desired bevel which is to be found upon the rafter. It is of course 30 obvious that this operation may be followed out finding any of the desired angles. 35 When it is desired to use the tool as a butt-gage the slides may be moved to the position illustrated in Fig. 1 while the rule would be carried as disclosed in the dotted lines in this figure. The rule may of course be positioned so as to extend below the base 1 for 40 the desired distance such for instance as two inches. The tool will then allow the bottom edge of the base to be placed against the edge of the timber or jamb while the rule may extend upon the face of the jamb. By 45 using a pencil or like instrument, the size of the notch which is adapted to receive the butt of the timber, may then be easily designated. It will also be seen that this device 50 may be used as a compass by releasing the indicating slide 9 and swinging the same so as to allow the point to extend down below the base 1 and then cause the slide to be again held in position by means of the set 55 screw 12. A pencil may then be positioned

so as to bear against the lugs 20 and 28 and held in this position by means of the clamping slide 10. The pencil will thus extend for a considerable distance below the base 1 and will have its point in approximately the 70 same plane as the point of the finger 13. The finger 13 may act as a pivot point while a pencil may be swung for forming a circle. In this manner it will be seen that the device may be used as a compass. If it is so 75 desired a pencil may be turned in the opposite direction and the device may be used as a spacing instrument. Furthermore, the slide 9 may be swung so as to allow the spur 19 to extend below the base and in this manner the slide may be used as a scratch gage by allowing the spur to be drawn across the 80 surface of an article.

It is of course obvious that the device may be used for other purposes than those set 85 forth but the same is used principally for the purpose of finding bevels upon rafters as is clearly disclosed by Fig. 3.

From the foregoing description it will be seen that a simple and efficient framing tool 90 has been produced which is formed so as to allow the rule to be easily gripped and held in an adjustable position and indicate a bevel which is adapted to be disclosed by placing the device and the rule upon a 95 rafter.

It is of course obvious that many minor 100 details of construction may be made in this device without departing from the spirit of the invention and it is therefore desired to include all such devices as properly come 105 within the scope of this invention.

The indicating slide 9 is provided with 110 graduations 34 which are adapted to constitute graduations for facilitating the finding of bevels and length of octagon rafters. The indicating line 35 will register with the graduations 34 for determining the position to which the slide 9 should be moved when necessary to find an octagon bevel.

What I claim is:—

1. A device of the class described comprising a frame, an indicating slide adjustably mounted upon said frame, a clamping slide adjustably mounted upon said frame an abutment carried by said frame, a rule carried by said indicating slide and said clamping slide for holding the same upon said frame and against said abutment, whereby the device will facilitate the finding of bevels and angles as desired. 115

2. A device of the class described comprising a frame, an indicating slide adjustably carried upon said frame, an auxiliary clamping slide adjustably carried upon said frame, a lug fixedly carried upon said frame at a spaced distance from said slides, a folding rule carried by said slides and lug, said lug adapted to form an abutment for said rule whereby said rule may be swung 120

slightly by said indicating slide and be held in engagement with said indicating slide and said lug by means of said clamping slide for determining a bevel or angle.

- 5 3. A device of the class described comprising a triangular frame the base portion of said frame being provided with a plurality of graduations, an indicating slide adjustably carried upon the base of said frame, said indicating slide provided with a tapering indicating finger, an ear formed integral upon said slide, a clamping slide adjustably supported upon said frame, said clamping slide provided with an overhanging portion, a lug fixedly secured upon the upper portion of said triangular frame at a spaced distance from said slides, said indicating slide adapted to be moved to allow said finger to be moved to the desired graduation, a rule abutting against said ear on said slide and said lug, said clamping slide being adapted to hold the rule in the position whereby the rule will extend diagonally across said frame so as to project beyond the side portion of said frame whereby an angle or bevel may be easily obtained.
- 10 4. A device of the class described com-
- 15
- 20
- 25

prising a triangular frame, said frame comprising a base having a reduced longitudinally extending rib formed integral thereon, a reduced shoulder formed integral upon said rib, an indicating slide adjustably carried upon said base, said base provided with a plurality of graduations, a tapering finger formed integral upon said slide, said slide being adapted to be moved so as to allow the finger to indicate the desired graduation, a clamping slide adjustably secured to said shoulder, said slides normally extending in parallel spaced relation to each other, a lug fixedly spaced upon said frame at a spaced distance from said slides, a rule positioned upon said frame, said clamping slide being adapted to hold the rule in engagement with said lug and said indicating slide whereby a desired bevel or angle may be easily obtained.

In testimony whereof I hereunto affix my signature in presence of two witnesses.

NELS OLSON.
